COIN-CONTROLLED DISPENSING MACHINE

Dan Neidig, Chicago, Ill., assignor to James H. Martin, Chicago, Ill.

Application May 2, 1950, Serial No. 159,513

6 Claims. (Cl. 194—57)

1

The present invention relates generally to coin-operated dispensing machines, and in particular to that type of dispensing machine having a plurality of selectable elements to be operated after insertion of one or more coins of predetermined value. In particular, the present invention relates to those parts of the mechanism related to the coin control and the selectability for the release of the merchandise being dispensed.

Dispensing machines of one certain type have one or more vertical magazines containing a vertical plurality of articles to be dispensed. Some dispense from the bottom of stacked material in the magazine. Others have the magazine divided into compartments, one of which empties at each selective operation for that magazine. The compartments may empty upwardly or downwardly, and the mechanism for delivery varies. The present invention is applicable to all these types of machines, but for the purpose of showing a complete mechanism, there is chosen for illustration a machine having a horizontal plurality of selectable magazines, and in each magazine a vertical plurality of compartments which empty upwardly.

In the machine herein illustrated, one or more articles to be dispensed singly or as a group is charged into a compartment for dispensing upon controlled release. Each compartment is constructed so as to effect discharge of its contents by action of some releasing mechanism which requires a mechanical operation or tripping to that end.

The release element is commonly one which moves step by step in the direction in which releasing progresses, and in moving one step the described mechanical release is effected. The illustrative machine has a releasing mechanism for each magazine which operates in a path along the magazine to effect progressive release.

For selectable merchandise in a single machine, it is conventional to expose to the customer a plurality of manual controls, of which one is selected for operation, which one is released for operation only after the proper coinage is inserted. It is conventional that the selected control is blocked if its magazine is empty, and in this blocked condition it is conventional to offer the customer the choice of selecting another manual control or of operating a "money-return" control to have the machine dispense the money inserted. Additionally, it is conventional in such machines that only one manual control may be selected and operated on a single coin-permit. Furthermore, in machines which offer manual

controls, which must be mechanically moved in an operating direction (as distinguished from electrical push buttons or equivalent mechanical push button releases), it is conventional to provide mechanism compelling movement of the control through a complete operating cycle, and to prevent any backing in a started cycle.

It is the general object of the invention to provide mechanism providing the above mentioned conventional features, which mechanism may be used in coin-operated dispensing machines having one or more magazines for choice or selection.

It is a particular object to provide a coin-control providing a resting station for a coin whereat it may function to permit dispensing, or wherefrom it may be recovered, at the will of the customer.

It is also a general object of the invention to provide improved mechanism for receiving a coin, and either for utilizing it for a dispensing operation, or for discharging it without use by a suitable return.

Various other objects and advantages of the invention will become apparent from the following description and explanation of the invention as it is illustrated by an embodiment thereof suitable for dispensing machines, as illustrated in the accompanying drawings, in which:

Fig. 1 is a front view of a dispensing machine showing five magazines having supports for articles to be dispensed, releasing mechanisms therefor, and at the bottom a portion of the master control mechanism connecting a selected magazine of the machine with the coin control.

Fig. 1a is a fragmentary side view of one of the release units.

Fig. 2 is a view of the lower portion of Fig. 1 taken from the reverse side showing mechanical connections for effecting and limiting selection of the operating bars, and in particular a master control member in normal position.

Fig. 3 is a fragmentary portion of the structure shown in Fig. 2 with the master control member at its innermost position, as moved from its outermost position shown in Fig. 2, illustrating the limitation of selection to one operating bar.

Fig. 4 is a fragmentary side view of the machine in the position shown in Fig. 1, in particular showing the master control member in an end view as related to coin control mechanisms.

Fig. 5 is a view similar to Fig. 4, but enlarged and with a cover plate of Fig. 4 removed to show parts pertaining to location of the coin, the figure being a section on the line 5—5 of Fig. 6.

Fig. 6 is a horizontal cross-section of the coin

control mechanism taken on the line 6—6 of Fig. 4.

Fig. 7 is a view similar to Fig. 5 showing certain of the parts moved to a position to discharge a coin as a return to the purchaser.

Fig. 8 is a fragmentary vertical cross-section taken on the line 8—8 of Fig. 4.

Fig. 9 is a vertical cross-section taken on the line 9—9 of Fig. 2.

Fig. 10 is an enlarged horizontal cross-section through the master slide, taken on the line 10—10 of Fig. 1.

It is to be understood that the invention is not limited to or by the illustrations of it shown in the drawings for the purpose of description and explanation of the invention in the appended claims.

Fig. 1 shows a front view of the interior of a dispensing machine having a horizontal plurality of vertical magazines. Each magazine is filled from the illustrated face with merchandise, and at this face are made available practically all of the moving parts. Each magazine may be as long as desired by increasing vertically the number of units or compartments therein. The five magazines shown are limited in size in the drawings to eight compartments only to facilitate the illustration and explanation, and any number may be horizontally aligned.

The body portion of the machine includes a back wall 10 to which are secured four spaced partition walls 11 between parallel end walls 12 and 13 forming the magazines designated 14, 15, 16, 17 and 18. Each vertical magazine has a number of article-supports vertically aligned, one for each compartment. Description of one compartment describes them all.

Each compartment has an article support pivoting on a horizontal axis in order to dump an article stationed thereon upon release of the support from its article-holding position. The support has at least a part of itself, or even the entire support, movable with respect to the body portion, which latter is provided appropriately with a detent structure to hold the support against dumping. Means is provided to move said part, or otherwise the entire support itself, away from said detent structure, thereby to permit pivotal movement on the horizontal axis with resulting dumping of the article supported thereby. The article support is normally biased to move into the position it assumes after dispensing, and the detent normally holds the support from biased movement into said position. Thereby after having dispensed an article, each support is normally located out of the path which is traveled by the next article to be dispensed from the magazine in a machine having release of articles progressing upwardly in the magazine.

The means to release each support for dispensing movement may vary widely in structure and operation, according to other features with which it is associated. Commonly, dispensing machines are designed for insertion of one or more coins to condition the machine for a single release, effected electrically or mechanically by operating some selective control where there must be a choice when numerous vertical magazines are involved. As illustrated, the releasing means is a structure which climbs upwardly step by step along the length of the magazine, thereby in its motion to move the article support from its holding detent. For picturesqueness in description, this particular form of release structure is herein called a "monkey."

Various forms of monkeys are used in machines

of the type illustrated. A known form is a guided monkey movable in one direction from end to end of a vertical magazine by a one-way sliding relation between the monkey and the machine body, and by a second one-way sliding relation between the monkey and a vertically reciprocable operating bar. Thus, movement of the operating bar in a half cycle of reciprocation, properly limited, moves the monkey a distance equal to the height of a compartment, and movement of the operating bar in the other half of its cycle is permitted while the monkey is held stationary for the one way connection with the machine body or casing. The mentioned sequence of the half cycles is not material and may be reversed. By this means, step by step movement of the monkey is effected by repeated reciprocations of the operating bar, and each movement of the monkey effects a dispensing release of a loaded support.

In the preferred illustrative embodiment shown in the drawing, there is a vertical series of axle rods 21 across the front face of the magazines 14 to 18 passing through the side walls 12 and 13 and fixed by heads 22 at wall 12 and by hooks 23 at wall 13. The axles 21 are equally spaced when there are identically sized compartments throughout the magazine. At each compartment on its axle 21 there is provided an article-support in the form of a platform 25 (top of magazine 18) having a flat article-holding main portion 26 inclined downwardly in the article-holding position toward rear wall 10, and thereby forming a shallow pocket for article A indicated thereon. The support is inclined to prevent forward sliding of article A during mischievous shaking of the machine as sometimes occurs in the hope of dislodging an article for free delivery. A front portion 27 of the support 25 lies above its axle 21, on which it bears through a channel-form piece secured beneath it, which piece has flat face 28 in contact with support section 27, and also has bearing ears 29 and 30. Said flat face 28 has a functioning edge designated 28' upon which acts a cam carried by the monkey to move the support horizontally as will be described. The support proper may be of light-weight metal and the channel part 28 is specifically provided to permit the bearing ears and edge 28' to be of harder metal.

To hold the support 25 in article-holding position, the forward portion 27 is held in said position by the face 28 resting under a fixed detent. The normal weight of the rear supporting section 26 acts by gravity to bias the support 25 to move into the dropped position designated 25a at the lower part of magazine 14. Each compartment has such a detent, and there is, therefore, a vertical plurality of such detents, each indicated by numeral 32 in magazine 18, under which lie the plates 28 of the forward support sections 27. The detents 32 are formed by cutting into a right angular flange 33 integral with partition wall 11 or side wall 12 on the left sides of the magazines as viewed in Fig. 1.

To release the support 25, the part thereof which is indicated under and held by detent 32 is movable with respect to the body portion of the machine, this being locally the adjacent wall 11 or 12 or its flange 33, or a detent 32 thereof, in order to escape the holding action of the detent.

One way to provide for such releasing movement is to slide the whole support 25 on its axle 21 to the right in Fig. 1. The support is narrower than the magazine width to permit such

sliding to the point of release. Spring means in the form of a coiled compression spring 35 about the axle 21 presses between the bearing ear 30 of the support and the adjacent right hand magazine wall 11 or 12. It is noted that the detents 32 have a functioning cam edge or face 34 inclined upwardly to the left in Fig. 1. This cam edge also functions on the edge 28' of the support to move the support to the right when resetting the machine by moving the support from its dropped position 25a back to its article-holding position.

The several releasing means effective for disengaging each support or part thereof from its detent 32 are shown in different positions vertically in Fig. 1. The preferred releasing means or monkey of the illustrated machine is now described. There is a vertically reciprocable operating bar for each vertical magazine, upwardly of which the monkey climbs. The bar illustrated is a right angle bar 41 (Fig. 2) having a flange 42 mounted to slide facewise along the forward portion of magazine side walls 11 and 12, and another flange 43 spaced forward of and parallel to the wall flange 33 which has the detents 32. The flange 42 of the operating bar 41 is slidably mounted on an adjacent side wall 11 or 12 by one or more headed pins 44 fixed in a wall 11 or 12, and by a corresponding elongated slot 45 (Fig. 9) in the flange 42 about such pin, of ample length to permit the desired extent of reciprocation. The monkey is slidably mounted on bar 41 and has a one-way sliding engagement therewith. The monkey also has a one-way sliding engagement with the body portion of the machine, particularly with flange 33 having the detents 32. These sliding engagements are effected by two pawl and ratchet means with one ratchet element on the bar 41 and one on the flange 33, and with the two pawls on the monkey. The pawls are preferably arranged for independent operation in the act of dispensing, but are related for simultaneous disengaging movements of the pawls from their ratchets by a single control to facilitate lowering the monkey and resetting the machine on reloading.

The monkey is designated generally by the numeral 51, and is illustrated in full front view in Fig. 1. As shown, it is carried solely by the vertical reciprocating bar 41 on which it is vertically slidable in both directions as mentioned above. In one direction it is freely movable on the bar 41 upwardly relative to the bar. Upward movement of the monkey along the magazine is permitted by moving the reciprocating bar 41 upwardly, with the monkey at this time stationary with respect to the operating bar 41.

A single control means is provided on the monkey to disengage both pawls from their normal relation to their ratchets, thereby to permit free sliding of the monkey relative to the two ratchets. Each pawl has a normal range of movement with respect to its ratchet. The preferred control means is effected by extending the normal range of movement of one pawl, and causing movement of said pawl in its extended range, to move the other pawl away from its ratchet.

The monkey is of simplified structure in the present instance consisting of a face or body portion with two pawls pivoted to the face portion, and a spring for each pawl. The face portion of the monkey is designated by the numeral 53 (see magazine 18). It is a metal plate deformed to provide an angular slot into which 75

fits the angular reciprocating bar 41 with a resulting sliding mounting of the monkey 51 on the bar 41. The face portion has deformed parts which bear slidingly on both faces of the flanges 42 and 43 of the reciprocating bar 41.

Looking at the monkey as illustrated in Fig. 1 one sees a vertical face portion partly covered by a bell crank member pivoted to said face 53. At the top of the face 53 there is a rearward integral flange 54 with a portion of it cut away to receive the edge of flange 43 of the bar 41, and with an end portion of the flange 54 positioned to engage on the inner face of flange 42 of the bar 41. Said flange 54 is also extended upwardly at its rear to form a vertical lug 55 as a dog for releasing the article-supports one at a time. The dog 55 has an inclined edge serving as a cam face 56, which in riding upwardly engages each edge 28' of an article-support 25, thereby to urge the whole support 25 laterally on its axle 21 against the spring 35, thereby to release an article.

Monkey face 53 is extended on the lower side by a rearward flange 57 suitably recessed to receive the edge of flange 43 slidingly as a bearing against the rear face of the flange 42 of bar 41. The left end of the monkey face 53 has a rearward vertical flange 58 positioned to lie slidingly against the outer face of reciprocating flange 42. The three flanges 54, 57 and 58, together with the monkey face 53, form an L-shaped slot through the monkey of suitable size to receive the right angular reciprocating bar 41 for the desired sliding relationship.

The pawl and ratchet structures may be variously arranged between the pertinent parts. The following is a description of the arrangement shown in the drawings. A lug 59 is struck forwardly at right angles from the monkey face 53 as a support for a horizontal pivot-rivet 60 for a depending vertical pawl 61 having an engaging tooth 62 at its end positioned to ride on the front face of the reciprocating flange 43. The pawl 61 is biased toward said flange by spring 63 (Fig. 1a). The flange 43 constitutes the ratchet for the pawl 61 by the provision of a vertical series of holes 64 (Fig. 1) spaced apart the same distance as the axles 21, which distance defines the vertical height of each compartment. The tooth 62 (Fig. 1a) has a cam edge or face 65 permitting vertical movement of the monkey upwardly of the bar 41 by the edge of a hole 64 camming the pawl 61 away from its ratchet. The tooth 62 also has an engaging edge or face 66 which prevents the monkey moving downwardly of the bar 41 by the tooth engaging a ratchet hole 64. Additionally, the pawl 61 has an inclined face 67 on its rear vertical edge such that a downwardly moving cam (later described) will cam the pawl 61 forward and move tooth 62 into non-engaging relationship with its ratchet holes 64.

Monkey face 53 has a manual control in the form of a crank member 69 pivoted to it by horizontal pin 70. The crank member as a pawl structure functions automatically in the dispensing action of the machine, but it is additionally constructed and arranged to facilitate manual control for disengaging both pawls from their ratchets. The crank member 69 has a manual control arm 71 normally biased by spring 72 into an acute angular relationship with the top flange 54 of the monkey, as shown generally in Fig. 1. Merely squeezing the control arm 71 and the flange 54 together against spring 72

effects the desired disengaging operations, directly with respect to the crank member as a part of one pawl, and indirectly by reason of a camming finger 74 carried by the other arm 75 of the crank member. It is said finger 74 which moves vertically downwardly (Fig. 1a) upon the inclined edge or face 67 of the pawl 61, as mentioned above, to disengage both pawls at once.

The downwardly directed arm 75 of the manual crank member 69 functions as a pawl by reason of an integral wide tooth indicated at 76 (see magazine 17), the same being biased to move to the left by action of tension spring 72. Tooth 76 is a piece of sheet metal integral with the arm 75 of the crank 69, bent backward at right angles from the arm 75. The tooth 76 lies approximately at a 45° angle to the vertical so that as the monkey 51 moves upwardly the tooth 76 is cammed to move against the force of spring 72 by contact with the edge of flange 33 having the detents 32, in the particular embodiment illustrated. However, this camming movement by said detents 32 is merely incidental and not functional. It is incidental to the provision of a ratchet structure along the same edge of flange 33 which contains the detents 32. The ratchet function is performed not by the detents 32 but by recesses 78 located just above the detents 32 as seen in Fig. 1. The ratchet is such that the monkey 51 may ride upwardly alongside the flange 33, but not downwardly of it unless the pawl tooth 76 is withdrawn from its ratchet. By pinching the crank arm 71 toward a flange 54 at the top of the monkey, the monkey 51 is liberated from both of its pawl and ratchet connections for free sliding movement on the bar 41. The finger 74 on arm 75 is so located that during normal pawl-and-ratchet action by tooth 76 over the edge of flange 43 (its ratchet), there is no camming action on the other pawl 61.

At the top of each reciprocating bar 41 there is a stop 80 indicated in Fig. 1, in the form of a lug struck from the flange 43. The stop 80 is so positioned that after the topmost support of a magazine has discharged its article, and when the reciprocating bar 41 has last returned to its uppermost normal position, the monkey is held stationary relative to the machine by the pawl tooth 76 being engaged in the uppermost notch 78 of its ratchet on flange 43. Normally the bar 41 could be lowered if the monkey were in a similar but lower position, but the location of stop 80 prevents an effective downward movement of the bar 41.

In Fig. 1 the operating bar 41 is connected to means for operating it. At the lower portion of Fig. 1 there is a horizontal slide 87 which moves to the left at each dispensing operation. The slide is so moved by manual depression of a push bar 88 (Figs. 1, 2, 3 and 9) which presents a horizontal flat platform to the public for operating it, as for example, when there is a coin inserted to operate the machine. The platform 89 engages the bottom end of the reciprocating bar 41 by insertion of the platform member 89 into a lateral slot 90 in a forward extension member 90' secured to each operating bar 41 (see Fig. 9). The operator's downward push on platform 89 operates the reciprocating bar 41 when and if the push bar 88 is liberated for downward movement, as by the insertion of a coin, through control means about to be described.

Means is provided to connect slide 87 with but one of the push bars 88 so that a purchaser after inserting a coin may push any selected one of the bars 88 and move slide bar 87, which is tied into the coin control. Slide bar 87 in Figs. 1 and 2 is in its rest position. In use it is moved from rest position to the position shown in Fig. 3, against a tension spring 91 mounted between the bar and wall 13.

To compel the bar to move through a half cycle before it may return to its position of rest, there is a fixed ratchet 92 on the casing and a reversible pawl 93 pivotally carried by the bar and normally biased into the position shown in Figs. 2 and 3 by a spring 93'.

Each bar 88 has a tension spring 88' from its lower end to a casing wall 94 to force the operating bars 41 and 88 into their uppermost positions. The lower end 96 of each bar 88 is narrower than the upper part to provide for two downwardly tapering shoulders 97, which act as cams to free a space for downward movement of but one bar 88 and at the same time indirectly to block like spaces for downward movement of any other bar 88. This is effected by an endwise chain of horizontal bars 98 shown in Figs. 1 and 9 mounted on a vertical casing wall 99 for horizontal sliding over a limited range as mounted under retaining channel strips 100 secured to said wall 99. Each bar has near each end a roller 101 to be cammed by a shoulder 97 on the nearest adjacent bar 88. The rollers extend through and move in slots 102 in wall 99. Each bar 88 moves downwardly between two such rollers 101 carried by each pair of adjacent bars 98, and in downward movement a selected bar 88 spreads the bars of the pair 98 if the latter are free to move. In case that an operation of bar 88 follows an operation of the same bar 88, the rollers 101 will already be spread to permit the second operation. Each bar 98 is free to move a limited distance suitable only to permit one of its rollers to move out of the path of one shoulder 97 while the roller on its opposite end is in the path of a shoulder 97 of its corresponding bar 88. Thus, only one bar 88 may be depressed, as shown in Fig. 3.

The slide 87 is slidably mounted on the inner face of front wall 99 by a pin and slot connection 99'. To move the slide 87 by a selected bar 88 there is provided a pin 103 on each bar 88 and an inclined slot 104 in which the pin rides, thus to move the bar 87 in a cycle of horizontal reciprocation for each cycle of vertical reciprocation of a bar 88. The pawl and ratchet 92-93 is thus effective to compel each bar 88 to move through a full cycle. The slot 104 is extended horizontally at the top by a slot 105 to permit the slide 87 to move through its cycle, by each such slot 105 riding along the stationary pins 103 of unselected bars. Slots 104 and 105 together form a 7-shaped slot as seen in Fig. 2, wherein each pin 103 is normally in a position to ride either down the slot 104 or relatively along the slot 105.

Means is provided to block movement of slide 87 except when a coin is inserted in the machine as a permit. This means is shown in the form of a fingerlike member pivoted to the slide for vertical movement and biased to a downward position in which it strikes a stop as the slide 87 attempts to carry it. This arrangement is such that a received coin in the machine is effective to lift the finger, as when it lies in the path of

means connected to this finger to act as a cam and move the finger away from its stop.

In Fig. 1 is a finger 110 is pivoted at 111 to the slide and it lies normally in the horizontal position shown. It has a free end 112 entered into a hole 113 in casing wall 13 (Figs. 1 and 7). The bottom edge 114 of hole 113 is a stop for a shoulder 115 on said finger. Tension spring 116 forces the free end 112 of the finger onto said edge 114, and permits the finger 110 to be raised so that shoulder 115 clears its stop 114 for movement of the slide 87 through its cycle. In Fig. 3 the finger shown is in raised position. A second finger 117 is rigidly connected to said finger 110 for movement therewith through pivot 111, as shown in Fig. 6. Finger 117 has an inclined tip 118 which rides up on the edge of a coin C as illustrated in Fig. 8.

The remainder of the mechanism pertains to handling the coin in relation to slide 87. On the right hand side of the machine (as viewed in Fig. 1) there is a coin selector box 120 of standard construction (see Fig. 4) for rejecting slugs and the like, and for dropping an accepted and proper coin C into a thin vertical chamber 121 therefor (see Figs. 4 and 5). Chamber 121 is defined laterally by walls spaced apart approximately the same distance as the thickness of a coin C. One wall is a cover plate 122 shown in Figs. 4 and 6, and removed in Fig. 5. The plate 122 has a hole 118' therein for entry of finger 117-118. The opposite wall of the chamber is a plate 123 of channel form mounted on wall 13, as shown in Fig. 6. Between these two walls of chamber 121 there is a vertical spacer strip 124 to confine one edge of coin C (Fig. 5) and opposite that is a triangular spacer plate 125 having vertical edge 126 for confining the coin edge, and an inclined edge 127 down which to roll the coin C when it is lifted for rolling as shown in Fig. 7. Inclined edge 127 leads to a chute 128 through which the coin is returned to the operator.

In coin chamber 121 there is a coin rest 130 on which the coin lies to position it for lifting the fingers 117 and 110 as mentioned above. The coin rest 130 extends across the chamber 121 and is movable in two directions. It may be withdrawn from its cross position in the chamber in order to drop the coin C into the treasury via the lower part of chamber 121, or it may rise in the chamber 121 to lift coin C into position for rolling down the incline 127.

To impart these movements to the coin rest 130, the latter is carried on an arm which pivots in a vertical plane for the lifting movement and which swings laterally for the dropping movement. The main arm is designated 131 and is pivoted for vertical swinging at a point intermediate its ends by pivot 132 entered in wall 123. The rear end of the arm 131 has a lateral pin or stud 133 in the path of means (later described) for depressing it to lift the coin rest for return of the coin as illustrated in Fig. 7. The arm 131 is held by spring 131' normally horizontally as shown in Fig. 5. So positioned, it carries a vertical pivot 134 offset in ears 135 for an extension 136 of the arm which may swing on said pivot into position 136a shown in Fig. 6. A leaf spring 136' urges the arm 136 against wall 123 as shown in Fig. 6. It is the arm 136 which carries the coin rest 130, which pulls the coin rest out from under the coin, and which lifts the coin rest for return of the coin. An arcuate slot 123' is provided in plate 123 as a path

for the coin rest 130. The upper part of said arcuate slot 123' is extended vertically to accommodate entry of the finger 117-118 when it rides on the coin before the coin is dropped.

5 The forward end 137 of arm 136 extends well beyond the coin rest 130 and toward slide 87 (see Figs. 6 and 8) into the path of a lug 138 carried by the slide 87. When there is a coin C on the rest 130, it raises finger 117-110 to permit the slide 87 to move in its cycle. This carries the lug 138 against the arm 137 and swings it laterally to the position 137a (Fig. 6) against spring 136', thus to move the coin rest 130 from under the coin to drop the coin into the treasury.

15 The means for action to return the coin is arranged to lift the coin as described and at the same time to lock the machine. Secured to the wall 13 there are two bars at right angles to each other, each of which slides longitudinally. One is a bolt bar indicated at 141 in Fig. 7 mounted under straps 142 and drawn horizontally to the rear by spring 143. The bolt bar functions as a lock in its forward position, with its front end 144 entered in a hole 145 (Fig. 6) in the slide 87 when the latter is in its position of rest. When a coin on the coin rest is to be returned, this bolt bar locks the slide against possibility of movement. The inner end of the bolt 141 is beveled as shown at 147, and it lies normally in a similarly shaped recess 153 (Fig. 4 and Fig. 7) of a second and vertical sliding bar 154 connected by pin 155 and slot 156 to the wall 13. The upper end of the bar 154 is connected by a pivot 157 to a manual control lever 158 pivoted at 159 and extending to the external front face of the machine for manual depression to return a coin. On such depression the downward movement of bar 154 acts upon the beveled edge 147 of the bolt 141 to move it into locking position, and then the bar 155 continues its downward movement against a tension spring 161 to bring its foot 162 on to the said pin 133, thus to move the pin down. Thereby the arm 131 is tilted to raise the coin rest 130 for return of the coin as described.

45 It is noted that the lowermost position of coin C is such that if another coin is introduced into chamber 121, it will roll down the incline 127 and be returned.

50 From the foregoing, it is clear that the arm 131 has numerous functions, in combination with a coin, and without a coin. When there is no coin on the coin rest 130, the machine is locked by the normal position of the finger unit 110-117. Any attempt to raise the coin-rest by operating lever 158, possibly to raise the finger unit, is preceded by action of bolt-bar 141 to lock the machine. The same locking occurs in a bona fide manipulation of return lever 158 to return a coin. A coin to be utilized functions on coin rest 130 to unlock the machine for operation, and the ensuing operation is effective to remove the coin rest and "take" the coin.

55 It is to be understood that numerous changes and modifications are contemplated as falling within the scope of the invention as set forth in the appended claims.

I claim:

1. In a coin-operated vending machine having a master member movable in a complete cycle of motion for each vending operation, a coin-control comprising means providing a pathway for gravity movement of the coin, a movable coin rest positioned normally to arrest said coin in said pathway, a movable lock normally locking

said master member against motion beyond a slight movement at the beginning of a cycle, said lock having a part arranged to move with said master member and located in said movement to make contact with a coin on said rest and be thereby moved into unlocking position to free the master member for its full cycle of movement, said coin rest being movable out from and back to coin-arresting position to permit dropping the coin past the normal position of the coin rest, means operated by the master member in that portion of its cycle of movement after the unlocking thereof to move the coin rest out of and back to coin-arresting position, means above said coin-rest providing a second pathway in which to return the coin to an operator, said coin rest also being movable to raise the coin thereon in said first pathway against gravity into position to enter said second pathway, and a manual control so to move the coin rest.

2. In a coin-operated vending machine, means providing a passageway for gravity movement of a coin edgewise into a treasury in the machine, a by-pass from said passageway for diverting the coin from entry into the treasury, a movable coin-rest below said by-pass normally positioned to arrest a coin in said passageway on its way to the treasury, said coin rest being movable from the passageway to pass the coin to the treasury and being movable in said passageway to raise the coin into position to roll into the by-pass, movable locking means associated with a coin on the coin rest to unlock the machine for operation and to lock the machine against operation in the absence of a coin on said coin rest, and means effective in the operation of the machine to move the coin rest from the passageway and back again in the meantime to pass the coin to the treasury, and manual means operable to raise the coin rest for discharging the coin into the by-pass.

3. In a coin-operated vending machine, means providing a passageway for gravity movement of a coin edgewise into a treasury in the machine, a by-pass from said passageway for diverting the coin from entry into the treasury, a movable coin rest below said by-pass normally positioned to arrest a coin in said passageway on its way to the treasury, said coin rest being movable from the passageway to pass the coin to the treasury and being movable in said passageway to raise the coin into position to roll into the by-pass, a lock to prevent operation of the machine, the combination of the coin rest with a coin thereon being arranged to unlock said lock and the lock being arranged normally to lock the machine in the absence of a coin on said coin rest, and means movable in the operation of the unlocked machine to move the coin rest from the passageway and back again, in the meantime to pass the coin to the treasury, a second lock to prevent dispensing operation of the machine, said second lock being normally unlocked, and manual means operable first to lock said second lock and then to raise the coin rest for discharging the coin into the by-pass.

4. In a coin-operated dispensing machine, means providing a coin chamber with one entry, with a treasury exit and with a return exit all arranged for normal gravity edgewise movement of the coin from the entry to the treasury exit, a coin rest normally positioned to arrest a coin thereon in its movement from the entry to the

treasury exit, said rest being movable out from under the arrested coin for delivering the coin to the treasury, and said coin rest being movable upwardly in the chamber to move the arrested coin into position for entering the return exit, means rendered active by a coin on said coin rest to move the coin rest temporarily out of the chamber by operation of the machine thereby to deliver the coin to the treasury, a lock to lock the machine against operation, and a manual control to move the coin rest upwardly in the chamber for delivering the coin to the return exit, said manual control being arranged first to move said lock to lock the machine and next to move said coin rest in the chamber.

5. In a coin-operated dispensing machine, means providing a coin chamber having one entry, having a treasury exit and having a return exit all arranged for normal gravity edgewise movement of the coin from the entry to the treasury exit, a coin rest normally positioned to arrest a coin thereon in its movement in said chamber from the entry to the treasury exit, said coin rest being movable out from under the arrested coin for delivering the coin to the treasury, and said coin rest being movable upwardly in the chamber to move the arrested coin into position for entering the return exit, locking means against operation of the machine having a part moved by a coin on said coin rest to unlock the machine for operation, means actuated by the machine in operation to move the coin rest temporarily out of the chamber, thereby to deliver the coin to the treasury, a second lock to lock the machine against operation, and a manual control to move the coin rest upwardly in the chamber for delivering the coin to the return exit, said manual control being arranged first to move said second lock to lock the machine and next to move said coin rest in the chamber.

6. In a coin-operated machine a movable member movable in one direction, a coin-rest pivoted on said member and movable with respect thereto in a different direction and movable with said member in motion of the latter in said one direction, said coin rest being located in the path of a coin inserted in the machine, said member being movable to move the coin rest in said one direction for moving the coin in one of two directions, means to move said member in said one direction, and means to move said coin rest relative to said member in stationary position for moving the coin in the second direction.

DAN NEIDIG.
